UNITED STATES PATENT OFFICE.

JAMES WOLFENDEN, OF LOCK HAVEN, PENNSYLVANIA.

RAILROAD RAIL AND JOINT.

SPECIFICATION forming part of Letters Patent No. 247,978, dated October 4, 1881.

Application filed September 6, 1881. (No model.)

To all whom it may concern:

Be it known that I, JAMES WOLFENDEN, a citizen of Great Britain, residing in Lock Haven, Clinton county, in the State of Pennsylvania, have invented certain new and useful Improvements relating to Railroad Rails and Joints, of which the following is a specification.

My improved joint is of that class in which a portion of the metal of each rail is removed 10 and the rails caused to overlap each other or splice together.

The invention consists in the manner in which the rails and clamps are formed and fitted into each other, and will be understood 15 from the following description and claims.

The following is a description of what I consider the best means of carrying out the invention.

The accompanying drawings form a part of 20 this specification.

Figure 1 is a plan view with a portion broken away. It shows the rails at the joints with proper relations without the inclosing clamps. Fig. 2 is a cross-section on the line R R in Fig. 25 1. Fig. 3 is a plan view of the joint. Fig. 4 is a cross-section on the line S S in Fig. 3. Fig. 5 is a horizontal section on the line T T in Fig. 4. Fig. 6 is the section on the line U U in Fig. 3. It is a section through the body of the 30 rail at a point removed from the joint.

Similar letters of reference indicate like parts in all the figures.

A A are the rails, certain portions being designated by further marks, as A' A'', &c., when necessary to distinguish them.

A' is the head. A'' is the broad base, sometimes known as the "flange," and A''' is the upright portion joining the flange and the head, universally known as the "web." The web A''' is 40 instead of being centrally placed in the rail, is placed one side of the center. In order to compensate for the disadvantage which this may be supposed to involve, I make the web a little thicker than would be esteemed economical for a corresponding rail with the web in the center. Having thus attained the conditions of a sound and every way reliable rail with a web out of center, I place the several rails 45 alternately in opposite positions—that is to say,

if the first of a given line of rails is placed 50 with its web out of center to the right, the second rail in that line which abuts or joints against it at the end is reversed in position, so that its web is out of center to the left. The third is again out of center to the right, and 55 so on alternately. The rails may be all formed in the same rolls and exactly alike, care being taken to simply place them alternately end for end. The webs are formed just so much 60 out of center that one face of each web is in the central line of the rail. These faces are made plane.

In preparing the splice I subject the rails to the action of saws, splining mechanism, or other proper machinery, with the metal of the rail either in a cold or hot condition, and operate so as to remove a sufficient length—say about eight inches—of one side of the head and at each end. This removal of a portion of the head and flange at each end of each rail is always on the side opposite to that which contains the web. Taking care to make the shoulder or offset where each splice ends square and perfect, the ends of the two rails apply together perfectly, and making proper allowance—say 70 an eighth of an inch (more or less) for expansion and contraction—the splice may be held together by any suitable means which will allow the proper end play for summer and winter, and a complete joint is produced, with a 75 smooth continuous head at the top and a smooth continuous flange at the bottom, but with the web of twice the usual thickness.

My clamps are formed of two equal parts, 80 each of which I will designate, when necessary, by the single letter M. I will designate certain parts of each by further marks M' M'', &c. These clamps M M are applied together in reverse positions, and held by transverse bolts P extending across below the flange of the rail. 85 They bind the splice firmly and strongly together without weakening any part of either rail by any hole or notch. Each clamp M is formed with an internal offset, M', which applies in the space beyond the end of the nearest adjacent web. It is, in other words, an internal thickening or offset in the clamp, made 90 just sufficient to match past one of the webs,

so that while the main inner surface of the clamp bears fairly and firmly against the stout web A^3 , which, by the position of the rails, lies on that side of the center line of the rail, this offset M' extends inward just sufficient to allow for the thickness of that flange and cause this portion of the clamp to bear against the web A^3 of the other rail. In other words, the inner faces of the clamps are fitted to match to the peculiarly-lapped condition of the two vertical webs A^3 , where they lie side by side, preserving the full thickness of each.

The upper portion of each clamp other than the offset M' is marked M^2 . The part of each clamp which extends out and back around the broad thin base A^2 of the rails is marked M^3 . A broad extension downward below the flange of the rails is marked M^4 . A slight internal lip at the bottom of each downward extension M^4 is marked M^5 . This lip M^5 need not be anything more than a slight thickening on the inner face of each clamp. When the clamps are applied together these lips M^5 face together and form a broad firm bearing, which serves as a fulcrum to allow the bolts P to draw the upper portions of the clamps very solidly together. The holes for the bolts P are formed through the downward extension M^4 , and are re-enforced with sufficient metal to loosely inclose the bolts and form a stout bearing, M^6 , on each side to receive the heads and nuts of the bolts P , as will be obvious.

The invention allows of the introduction of thin or thick rubber, felt, or other elastic material above or below the flange A^2 of the rail or on the inner faces of the firmly-bearing portions M' M^2 ; but I do not esteem such an addition generally expedient. I prefer that the parts bear directly together, metal and metal, and that they are nicely shaped to afford as firm a bearing as possible, to produce a final effect as nearly that of a single massive shape of metal as can be obtained.

Railroad practice proves that the joints, however thickened and fortified, are still not only the most imperfect portions of the track by way of introducing roughnesses and offsets in the paths for the wheels, but also in being more liable to fracture and looseness than other portions of the track, and all ordinary joints are more elastic than the main portions of the rails. My joint avoids danger of looseness, and by the duplication in the thickness of the web and the firmness with which the parts are supported by my clamping means gives a rigidity equal to and somewhat greater than that of the main body of the rail.

Modifications may be made in the forms. I can vary the thickness of the whole or all of the various parts. The bottom lip, M^5 , can be reduced or dispensed with altogether. I can employ a greater number of bolts P than two. One stout bolt firmly set up and reliably locked may be found sufficient.

The material of all the parts may be varied. I can use hard or soft iron, all the grades of steel or semi-steel, or various combinations of these favorite metals. My invention may be used with steel-headed rails. In the rare cases where the head or the whole rail shall be hardened steel the shaping can be fully completed beforehand.

I do not confine myself to any precise mode of shaping the parts. I propose to make the clamps of cast-steel or semi-steel by the process of casting complete; but they may be made by forging by suitable dies in trip-hammers or drop-presses.

The invention may be applied to double-headed or triple-headed rails by simply providing for the thick and rounded portions which such rails present at the bottoms.

I claim as my invention—

1. The rail-joint clamp described, having the top bearing-surface, M^2 , lateral folded parts M^3 , deep central web, M^4 , bottom bearing rib or surface, M^5 , and bolt-bearings M^6 , adapted to serve relatively to each other and to the confining-bolts P and inclosed rails as herein specified.

2. The railway-joint clamp described, having the internal projections, M' , adapted to abut against the ends of the webs of the rails, the upper bearing-surface, M^2 , foot-embracing portion M^3 , bottom flange, M^4 , lip or bearing-surface M^5 , and one or more bearings, M^6 , arranged to receive the confining-bolts P , all substantially as herein specified.

3. The railway-joint described, having the clamps M , formed as shown, and the confining-bolts P , in combination with each other and with rails having webs A^3 out of center, all arranged to serve as and for the purposes herein specified.

In testimony whereof I have hereunto set my hand, at New York city, this 27th day of August, 1880, in the presence of two subscribing witnesses.

JAMES WOLFENDEN.
